DESIGN FOR A HANDLE POST

Joseph H. Plotkin, Chicago, Ill., assignor to Oshkosh Trunks, Incorporated, Oshkosh, Wis., a corporation of Wisconsin

Application April 8, 1940, Serial No. 91,540

Term of patent 14 years

To all whom it may concern:

Be it known that I, Joseph H. Plotkin, a citizen of the United States and a resident of Chicago, in the county of Cook and State of Illinois, have invented a new, original, and ornamental Design for a Handle Post, of which the following is a specification, reference being had to the accompanying drawing, forming part thereof.

I claim:

The ornamental design for a handle post, substantially as shown.

JOSEPH H. PLOTKIN.
